UNITED STATES PATENT OFFICE

CHARLES V. GODDARD, OF BROOKLYN, NEW YORK.

DESIGN FOR A BUCKLE.

SPECIFICATION forming part of Design No. 13,898, dated May 8, 1883.

Application filed January 18, 1883. Term of patent 7 years.

To all whom it may concern:

Be it known that I, CHARLES V. GODDARD, of Brooklyn, in the county of Kings and State of New York, have invented certain Improvements in Designs for Buckles, of which the following is a specification.

My invention consists in an improved design for that class of buckles which are ordinarily used upon articles of clothing, particularly vests and pantaloons.

Referring to the accompanying drawings, Figure 1 represents in perspective a buckle embracing my improved design. Fig. 2 is a cross-section of the same on the line *x x*.

15 The design consists of the two upper members, A and B. The member A consists of the flattened or widened front plate, *a*, having its two ends curved backward and inward, and terminating in eyes or lips *b*. The front plate, *A*, is of the sectional form represented in Fig. 2, with a raised rib or lip, *c*, along the front edge. It is also provided on the upper surface with a waved or serrated surface, *d*; but this is not essential. The rear section, *B*, consists of a 20 round strip or wire having its two ends *e* bent forward and inward through the eyes *b*, and thence extended inward parallel with each other in position to rest upon the upper surface of the front plate, *c*, as shown. It will be observed, 25 as a peculiarity of these arms or prongs *e*, that their forward ends are brought to sharp points in a conical or conoidal form, being tapered on two sides. It will be observed, as a further peculiarity, that the arms or prongs are curved 30 upward between their forward ends and the

points at which they pass through the eyes *b*, this curvature being such that the extreme points or terminations will rest upon the face of the front plate, *a*, and present the appearance represented in Fig. 2, the points lying below the surface of the front rod, *c*.

I do not claim, broadly, as my design the combination of the members A and B, having the general outline or configuration represented. Neither do I claim the waved or serrated surface *d*, individually considered, this feature being a subordinate one, which may be omitted, if desired. I believe myself, however, to be the first to produce a buckle which, considered as a whole, presents to the eye an appearance such as represented in the drawings.

The essential feature of my design consists in the upward curvature of the arms or prongs *e*, combined with the conical points or ends arranged to bear upon the base *a* at their extreme ends, as shown.

Having thus described my invention, what I claim is—

1. A design for a buckle, substantially as described and shown. 63
2. In a design for buckles, the section A, having the raised rib *c*, combined with the section B, having the arms *e*, of round section, said arms curved longitudinally, and having the conical ends, as described and shown.

CHARLES V. GODDARD.
